UNITED STATES PATENT OFFICE.

ALBERT H. RICE, OF DES MOINES, IOWA.

SILO-DOOR.

1,068,701.

Specification of Letters Patent. Patented July 29, 1913.

Application filed November 29, 1912. Serial No. 734,201.

To all whom it may concern:

Be it known that I, ALBERT H. RICE, a citizen of the United States, residing at Des Moines, in the county of Polk and State of Iowa, have invented a certain new and useful Silo-Door, of which the following is a specification.

The object of my invention is to provide a silo door of simple, durable and inexpensive 10 construction.

It is well known that in silo construction it is desirable to secure a door so constructed and arranged with relation to the frame of the silo as to allow for expansion and 15 contraction.

It is, therefore, my object to provide a silo door so constructed and arranged as to provide for this expansion and contraction.

More particularly, it is my object to provide a silo door having slideable side members which may be adjusted with relation to the door and to the silo wall and securely locked in position when the door is installed. In this connection, it is my purpose to provide 25 simple and durable mechanism, for operating the sliding members of the silo door sections.

It is a further object to provide a silo door section of simple, durable and inexpensive 30 construction, constructed and arranged to fit snugly and firmly the opening in the silo wall, said door being preferably of the type having vertical members and horizontal members, as shown in order that it may 35 withstand moisture and expansion and contraction.

My invention consists in certain details, in the construction, arrangement and combination of the various parts of the device, wherefore 40 by the objects contemplated are attained, as hereinafter more fully set forth, pointed out in my claims and illustrated in the accompanying drawings, in which:

Figure 1 shows a front elevation of a part 45 of a silo equipped with door sections embodying my invention. Fig. 2 shows a vertical, transverse, sectional view through the silo showing my door sections from the side. Fig. 3 shows a large, detail view of the 50 means for operating the sliding side members of my door. Figs. 4 and 5 show detail, sectional views of my door sections. Fig. 6 shows a horizontal sectional view of part of the silo door and wall, showing means by 55 which the side members of the door are moved, and Fig. 7 shows a horizontal, sec-

tional view of one of my doors and part of the silo wall.

In the accompanying drawings, I have used the reference numeral 10 to indicate, generally, the staves of the silo wall which are held together by means of the retaining bands or rods 11. The silo is provided with the ordinary door opening, extending from top to bottom. The edges of the silo wall, 60 along the door opening, are preferably formed with a beveled portion 12 over the inner half of the edge of the silo wall, the bevel extending from the inside outwardly and toward the middle of the door openings, 65 and with a half round or nosing 13 at the outer portion of the edge of the wall.

I will now describe one of my improved door sections.

The body of the door section is made of a front portion of vertical strips 14 and a back portion of horizontally arranged strips 15. In wood stave silos, the combined thickness of the strips 14 and 15 is approximately the same as the thickness of the silo wall 70 members 10. The side edges of the horizontal strips 15 are beveled to fit the beveled edges 12 and the edges of the vertical strips 14 at the side of the door section are made

concave to fit the half round 13, as clearly 75 shown in Figs. 6 and 7. The members 14 are preferably slightly thinner than the half round 13, above mentioned, so that a tight joint may be formed, as hereinafter more fully set forth. The outer vertical strip or member 14, at each side of the door section, is slidably mounted on the body of the door section in the following manner: A vertical plate or metal strip 16 is secured to each 80 slideable member 14 on the outer surface at the edge thereof, adjacent to the side of the silo door opening in such position and manner that when forced laterally with the member 14, it tends to draw the members 15 outwardly, thus forming a very tight joint.

Secured to each upright strip 14, which is adjacent to the movable strip 14, is a wider plate 17 which extends from the top to the bottom of the door section and is of sufficient width to overlap the movable section 14 and to cover the gap between the movable section 14 and the adjacent fixed strip 14. Mounted on each movable strip 14, approximately at the center thereof, is a metal block or body 18 having a laterally extending flange 19 which is secured to the movable strip 14 in the following manner. The

flange 19 is provided with a horizontal elongated slot 20. The surface of the flange 19 is roughened or corrugated at 21, as clearly shown in Fig. 3.

5 Extending through each movable member 14 and through the metal strip 16, through the slot 20, to a point outside of the flange 19, is a bolt 22. At the outer end of the bolt 22, adjacent to the flange 19, is a washer 10 23 having its inner surface rough, as shown in Fig. 6, to engage the corrugated portion 21 of the flange 19. On the outer end of the bolt 22 is a nut 24. It will, therefore, be seen that the flange 19 of the block or 15 body 18 is secured to the movable strip 14 on each side of each door section by means of the bolt 22 and that the body 18 and the flange 19 may be adjusted laterally with relation to the movable strip 14 by loosening 20 the nut 24 and the bolt 22 and sliding the body 18 and flange 19 laterally. The purpose of the elongated slot 20 is now seen.

Formed in the block or body 18 is a horizontal opening provided with a screw thread 25 25 of very wide pitch. On each of the vertical strips 14 of the door section, adjacent to the movable strip 14 on each side of the door section is a block or body 26 having a laterally extending flange 27 se- 30 cured to the strip 17 and the fixed member 14. Rotatably mounted in the block 26, on each side of each door section, is a shaft 28 which is also extended through the opening in the block 18 and is provided with a screw 35 thread 29 having a pitch to correspond to the pitch of the screw thread 25.

Connecting the shafts 28, and preferably formed integral therewith, are crank arms 30, connected by a rod 31. The outer portion of the flange 27 is concave, as shown in 40 Figs. 3, 4 and 6, and formed on the upper and lower portion of each flange 27 are shoulders 32 and 33. The shoulder 32 is so constructed and located that when the crank 45 30 and the rod 31 are at the upward limit of their movement, the cranks 30 will rest against the shoulder 32, thereby holding the rod 31 slightly spaced apart from the vertical members 14 of the door section. The 50 shoulder 33 extends outwardly farther than the shoulder 32 so that when the cranks 30 are in the lower position of their movement, the cranks 30 will be held in position extending downwardly and slightly outwardly 55 from the silo, as shown in Fig. 4 and Fig. 1, thereby forming a ladder. At the bottom of each door section, the members 14 and 15 are beveled to form a channel, preferably having the form of an inverted V, in cross 60 section, as shown in Figs. 2 and 5, and at the top of each door section, said members 14 and 15 are beveled from their outsides upwardly to their insides to fit said channel. At their upper ends, the plates or strips 17 65 are inclined upwardly and inwardly at 35

to fit into the channel heretofore mentioned and also to cover the space between the movable and fixed door members, as shown in Fig. 5.

In the practical use of my improved door sections, each section is placed in position from inside the silo with the rod 31 at the upward position of its movement. The members heretofore described are so arranged that when the rod 31 is then moved to the lower position of its movement, the movable member 14 will be moved to position adjacent to the jamb of the silo door, as shown in Figs. 6 and 7. In this connection, it may be noted that the strip 16 extends slightly beyond the movable member 14 so as to engage the outer surface of the silo wall, as shown in Fig. 6, when the door section is in position and the door open as hereinbefore mentioned. By means of the slot in the flange 19 and the bolt 22, the body 18 may be adjusted laterally relative to the movable member 14, thereby enabling me to move the movable member 14 just the right distance to make the door section fit the 90 door opening. The flange 19 is so constructed and arranged that when the door sections are installed in a silo or other structure, they engage the beveled outer edges of the door frame, as shown in Figs. 3, 5 95 and 7, thereby locking the door sections in position and helping to draw the members 15 against the frame for forming a tight joint. When the door section is in place, the silo is filled with ensilage 36. It will be 100 noted that the space between the movable and fixed members 14 is covered by the plate 17 and at the upper end of each section, said space is covered by the portion 35 of the plate 17.

The shape of the edges of the door sections may be changed as desired so long as tight joints are formed between the adjacent sections, and so long as the edges of the door sections snugly fit the edges of the door 110 opening. It will also be noticed that the movable side member is centrally pivoted so that if the door opening is not exactly perpendicular, the movable members will still fit properly.

115 It will be understood that many variations may be made in the details of construction of my improved silo door, it being my intention to cover any form of the device included within the scope of the appended 120 claims. The advantages of my improved silo door are numerous.

One of the chief problems in silo construction is to secure a tight joint around the door. I secure this by the form of the edges 125 of the door opening and of the door sections and by means of the slideable or movable members 14. Another problem which is always met in silo construction is that of providing for expansion when the silage heats. 130

With my door, the cranks 30 are made of metal which has some resiliency and in case of expansion said cranks may be sprung slightly, thereby avoiding any breaking of the parts.

My improved door is quickly and easily installed in position, is of comparatively simple and durable construction and enables me to secure a very tight joint. The crank arms 30 and the connecting rod 31 not only serve for the purpose of giving me considerable leverage for operating the movable members 14, but they also form a ladder used on silos. The upper door sections may be easily and readily removed as the ensilage is taken from the silo, or shoved up and left in the openings.

In the following claims I have designated the movable strips 14 as sealing strips for the reason that they serve the purpose of engaging the inner edges of the silo door frame and forming a tight joint or seal with the frame.

The combination of the resilient shaft with its crank, the movable sealing strips and the screw thread connection between the strips and ends of the shaft, serves to produce a very advantageous result, in that when the silo door is in place and the silo expands the sealing strips will inevitably be pushed inwardly toward each other. If the connection between the shaft and the sealing strips were such that this inward pressure would operate to elevate the crank, then when the silo again expanded the sealing strips would possibly not follow outwardly and maintain a tightly sealed joint, but on account of the fact that the screw connection is immovable against pressure upon the outer edges of the sealing strips, then when this pressure is applied, the resilient shaft will yield at the crank and thus avoid any injury to the parts, then when contraction of the silo takes place the yielding crank will operate to cause the sealing strips to move outwardly and maintain a tight joint with the edges of the silo door.

I claim as my invention:

1. The combination with a silo door, of sealing strips at the side edges thereof, capable of movement outwardly to engage the inner faces of a silo door frame, and also capable of moving inwardly away from such sealing engagement, a shaft made of resilient material rotatably mounted on the silo door and bowed to form a crank member or handle capable of use as a ladder, there being a spiral screw connection between the ends of the shaft and the said sealing strips whereby when the crank member or handle is elevated the sealing strips will be moved inwardly and when the crank member or

handle is moved downwardly toward position for use as a ladder the sealing strips will be moved outwardly to engage the inner edges of a door frame and to form a tight joint therewith and whereby the said sealing strips will be locked by said spiral screw threads against movement toward each other by pressure upon the outer edges of the sealing strips.

2. The combination with a silo door, of sealing strips at the side edges thereof, capable of movement outwardly to engage the inner faces of a silo door frame, and also capable of moving inwardly away from such sealing engagement, a shaft made of resilient material rotatably mounted on the silo door and bowed to form a crank member or handle capable of use as a ladder, there being a spiral screw connection between the ends of the shaft and the said sealing strips whereby when the crank member or handle is elevated the sealing strips will be moved inwardly and when the crank member or handle is moved downwardly toward position for use as a ladder the sealing strips will be moved outwardly to engage the inner edges of a door frame and to form a tight joint therewith, and whereby the said sealing strips will be locked by said spiral screw threads against movement toward each other by pressure upon the outer edges of the sealing strips, and means for adjusting the said sealing strips relative to the said spiral screw connections.

3. The combination with a silo door, of sealing strips designed to engage the inner edges of a door opening, a shaft rotatably mounted on the silo door having a crank member or handle capable of use as a ladder, lugs fixed to the sealing strips and provided with projections designed to overlap the exterior of a silo door frame, said lugs being also provided with screw threaded openings and the ends of said shaft being screw threaded and inserted in the said screw threaded openings, and said parts being so arranged that when the crank member or handle is in an elevated position the sealing strips and lugs will be disengaged from the silo door frame and when the crank member or handle is lowered to position for use as a ladder the sealing strips will form a sealing connection with the inner faces of a door frame and the lugs will overlap the exterior of a silo at the door frame and prevent inward movement of the door.

Des Moines, Iowa, November 25, 1912.

ALBERT H. RICE.
